UNITED STATES PATENT OFFICE

131,187

DESIGN FOR A SCARF OR SIMILAR ARTICLE

Cye Kronfeld, Los Angeles, Calif.

Application December 5, 1940, Serial No. 97,087

Term of patent 14 years

To all whom it may concern:

Be it known that I, Cye Kronfeld, a citizen of the United States, residing at Los Angeles, in the county of Los Angeles, State of California, have invented a new, original, and ornamental Design for a Scarf or Similar Article, of which the following is a specification, reference being had to the accompanying drawing, forming part thereof.

The figure is a plan view of a scarf in extended form, showing my new design.

I claim:

The ornamental design for a scarf or similar article, substantially as shown.

CYE KRONFELD.
